DICTATING AND REPRODUCING
APPARATUSFederico Nicolas Del Ponte, Buenos Aires,
Argentina

Application April 1, 1931, Serial No. 526,948

1 Claim. (Cl. 181—21)

The present invention relates to microphones, and more particularly has reference to microphones provided with a sound-collecting chamber, the interior of which is lined with sound-absorbing material.

The major object of the present invention is to provide a microphone consisting of a truncated pyramidal sound-collecting device provided with a microphone capsule at the apex 10 portion thereof and having the interior of the sound-collecting device lined with sound-absorbing material.

Another object of this invention is to provide a microphone comprising a truncated pyramidal sound-collecting device, the interior of which is lined with sound-absorbing material maintained under tension.

With these and other important objects in view, which may be incident to my improvements, the invention resides in the parts and combinations to be hereinafter set forth and claimed, with the understanding that the several necessary elements comprising my invention may be varied in construction, proportions and arrangement, without departing from the spirit and scope of the appended claim.

In order to make my invention more clearly understood, I have shown in the accompanying drawing means for carrying the same into practical effect without limiting the improvements in their useful applications to the particular constructions which, for the purposes of explanation, have been made the subject of illustration.

35 In the drawing:

Figure 1 is a vertical sectional view of a microphone constructed in accordance with the present invention; and

40 Figure 2 is another sectional view taken on line 2—2 of Fig. 1.

Referring to the drawing, in which similar reference characters are used to designate corresponding parts, I have shown a microphone 45 consisting of a truncated pyramidal sound-collecting device 1 which may be formed of wood or other suitable material. At the apex portion of the truncated pyramid, I have provided a microphone capsule 2 which may be of any of 50 the well-known types now in use. In order to avoid undesirable effects in the sound transmitted to the microphone capsule 2, the interior of the truncated pyramidal collector 1 is provided with a membrane 3 of india rubber or 55 felt. By making the membrane 3 of suitable

material, the sound effects will be greatly improved.

In accordance with the present invention, it is essential that the membrane 3, which is of a shape corresponding to that of the collector 1, be maintained under tension. For this purpose, the membrane is secured to the base of the pyramidal collector 1 and is further secured at the apex thereof to a tensioning member 4 which, in turn, is connected to the apex portion of the collector 1. The tensioning member 4 may be formed of india rubber or other suitable material which will serve the purpose of maintaining the membrane 3 under tension.

A microphone constructed in accordance with the present invention prevents the impingement of undesirable sounds upon the microphone capsule 2, these undesirable sounds being deadened by the elastic effect of the membrane 3.

While I have shown and described the preferred embodiment of my invention, I wish it to be understood that I do not confine myself to the precise details herein set forth by way of illustration as it is apparent that many changes and variations may be made therein by those skilled in the art, without departing from the spirit of the invention or exceeding the scope of the appended claim.

In a sound recording system, a microphone having the shape of a truncated pyramid, the 85 microphone comprising a box, a truncated pyramidal flexible sound-absorbing membrane within the box, means adjacent the apex of the box for tensioning the flexible membrane to the box, and a microphonic capsule at the truncated 90 apex of the box.
